US00D928820S

(12) **United States Design Patent** (10) Patent No.: **US D928,820 S**
Bodduluri et al. (45) Date of Patent: **** Aug. 24, 2021**

(54) **DISPLAY SCREEN OR PORTION THEREOF WITH GRAPHICAL USER INTERFACE FOR A RADIATION TREATMENT**

- (71) Applicant: **Zap Surgical Systems, Inc.**, San Carlos, CA (US)
- (72) Inventors: **Radhika Mohan Bodduluri**, Palo Alto, CA (US); **Bernadette Seijo**, San Carlos, CA (US); **John R. Adler, Jr.**, Stanford, CA (US); **Ben Chen**, San Carlos, CA (US); **Hongwu Wang**, San Carlos, CA (US); **Jin-Wu Wang**, San Carlos, CA (US); **Dezhi Liu**, San Carlos, CA (US); **Cheng-Chieh Tsai**, Taipei (TW); **Yun-Yi Ting**, Taipei (TW); **Ya-Shan Lin**, Taipei (TW); **Yan-Ling Liu**, Taipei (TW)
- (73) Assignee: **Zap Surgical Systems, Inc.**, San Carlos, CA (US)
- (**) Term: **15 Years**
- (21) Appl. No.: **29/711,248**
- (22) Filed: **Oct. 29, 2019**

CLAIM

The ornamental design for a display screen or portion thereof with graphical user interface for a radiation treatment, as shown and described.

DESCRIPTION

FIG. 1 shows a display screen or portion thereof with graphical user interface for a radiation treatment; and, FIG. 2 shows the display screen or portion thereof with graphical user interface for a radiation treatment of FIG. 1 in an environment of a radiation treatment system display. The portions shown in broken line or bounded by broken line are directed to environment and form no part of the claimed design.

1 Claim, 2 Drawing Sheets
